UNITED STATES PATENT OFFICE.

ZOFIA YACHNO, OF WALNUTPORT, PENNSYLVANIA.

FACIAL DEVICE.

Application filed August 22, 1922. Serial No. 583,646.

To all whom it may concern:

Be it known that I, ZOFIA YACHNO, a citizen of the United States of America, residing at Walnutport, in the county of Northampton and State of Pennsylvania, have invented certain new and useful Improvements in Facial Devices, of which the following is a specification.

This invention relates to new and useful improvements in facial devices and has particular reference to devices adapted to be used by women of a matured age and those having facial blemishes such as sagging cheeks, flesh wrinkles, or double chins, whereby these difficulties may be overcome.

The primary object of this invention is to devise an article of the above character that may be readily worn upon the head of women in such a manner that the same will be entirely hidden from view by the hair of the wearer thereof and whereby when the device is once applied all wrinkles or sagging flesh may be entirely overcome.

A further object of this invention is the production of a device of this character that is both simple in its form and inexpensive in manufacture, and a device that may be readily sold to the trade to be then used by them for the above purposes.

With the above general objects in view and others that will appear as the nature of the invention is better understood, the invention consists in the novel form, combination, and arrangement of parts hereinafter more fully described in connection with the accompanying drawings, and in which like designating characters refer to corresponding parts throughout the several views.

In the drawing:

Fig. 1 is a side elevational view showing the device in an applied position.

Fig. 2 is a plan view of the device, the same being shown in a slightly extended dotted line position,

Fig. 3 is a transverse sectional view upon line 3—3 of Fig. 2,

Fig. 4 is a similar view taken upon the line 4—4 of the same figure,

Figures 5 and 6 are also sectional views taken upon the lines 5—5 and 6—6 respectively, of Fig. 2.

Referring more in particular to the several views, my device comprises a central substantially U-shaped member 1 formed from two L-shaped members 2 and 3, their lower ends adapted to overlie each other

and being provided with aligned longitudinally extending slots 4, a rivet 5 or the like, passing therethrough for permitting a sliding or pivotal movement of the members 2 and 3 towards or away from each other. Pivotedly secured to the slotted ends of the side members 2 and 3 and by the same retaining means 5, are two arm members 6. These arms are formed from sections 7 and 8, the sections 7 being provided with a longitudinally extending slot 9, and the sections 8 having a locking means 10 carried thereby and adapted to engage through the said slot 9 whereby the length of the arms 6 may be adjusted to any desirable degree and retained in this adjusted position by the locking means 10, the latter means not being fully shown.

Secured in any suitable manner to the opposite forward ends of the arm members 2 and 3 and extending at right angles thereto are other arm members 11. The inner ends of these arms are adapted to extend inwardly of the U-shaped member 1, formed from the side arms 2 and 3, and are arranged to overlie each other. These arms are likewise provided, for a portion of their length, with a longitudinally extending slot 12, a rivet 13 or the like adapted to pass therethrough for retaining these arm members in any desired adjusted position.

The outer free ends of the arms 6 and 11 are each provided with a rectangular shaped pad 14, these pads adapted to contact with the face of the wearer in a manner hereinafter more fully described, and are so positioned upon the ends of the arms 6 and 11 as to be vertically movable thereon, in such a manner as to allow these pads to engage the face of the wearer under different degrees of pressure for firmly retaining these pads in their proper applied position. These pads 14 are suitably retained within pan-shaped members 15, the bottom walls of which are each provided with a depending U-shaped bracket 16 for slidably engaging over its associated arm 11 or 6. Screw threadedly received within each arm 6 and 11 is a set screw 17 its upper end adapted to engage the adjacent bottom wall of the pan-shaped member 15 and its opposite end adapted to extend through the U-shaped bracket 16 and having an annular-shaped thumb piece 17 thereon, whereby through the medium of the screws 17 the pads 14

may be adjusted towards or away from their

associated arm, for adjusting the degree of pressure of the pads upon the face of the user.

In Figure 1 of the drawings I have endeavored to clearly disclose the device applied in its proper position upon the head of the user, and the manner of so applying the device will be now fully described by me.

10 Before the application of my invention, to its operative position, it is preferred that the hair of the wearer will be extended backward upon the head or in any other desirable undressed position. The device 15 is now applied in a position as shown in Figure 1, with the exception of the fact that the lower arm members 6 are extended in such a position as not to engage or contact the skin. The loose or flabby flesh is 20 then forced upwardly by the fingers for engaging beneath the pads 14 upon the side arms 11 at which time sufficient pressure may be exerted upon these pads for firmly engaging the same upon the face. The other 25 arms 6 are then adjusted to the desired length and are adapted to extend under the ear lobes to position beneath the other pads 14 on the upper arms 11. Any additional sagging or drooping flesh that may 30 be found is also raised upwardly by the fingers so as to engage beneath these other pad members at which time these pads may be likewise positioned upon the face under any desired degree of pressure.

35 The L-shaped central arms 2 and 3 forming the U-shaped member 1, and the pad carrying arms 11 and 6 are adapted to be formed from a substantially light flexible material such as spring steel or the like, 40 and these separate elements are so formed as to assume the contour of one's head as shown in Figure 1, it being noted that the device although being so shaped may be adjusted so as to be used by women having 45 different sized heads, it also being noted that after the device has been positioned in an operative relation, the hair of the wearer may be suitably dressed upon the head thereof so as to completely cover the entire 50 device for absolutely preventing the same from being seen. If found desirable, coil springs 18 may be positioned between adjacent arms 6 and 11 for normally tending to hold the arms in operative position shown 55 in Fig. 1, each of the arms being provided with perforations 19 for receiving hooked ends of these springs, (not shown).

60 It is understood that coil springs 18 are of light construction and their purpose is not to draw arms 6 and 11 toward each other, or to exert any tension thereupon, but merely to retain them in operative position as shown in Fig. 1 and to prevent the spreading apart of the arms. It is further 65 understood that the device is made of flexi-

ble material, preferably from clock spring metal, and therefore the device will snugly fit over the head of the wearer, and thus pads 14 will always tend to pull upon the skin by virtue of the construction of the pads as 70 shown in Fig. 6, and also by virtue of the action of the flexible members 8 and 11.

The lower pad 14 normally rests under the lobe of the ear or slightly in front thereof, at user's discretion. It is preferable to 75 have the lower pad 14 covered by the ear lobe, and while in this position the pad's pressure tends to raise the ear somewhat, but this of course is not objectionable and does not disfigure the ear or the face. 80

While there is herein shown and described, the preferred embodiment of the present invention, it is nevertheless to be understood that minor changes may be made therein without departing from the spirit 85 and scope of the invention as claimed.

What I claim as new is:—

1. In a device of the class described comprising a plurality of adjustable arms, flesh engaging pads associated with said arms, 90 and means for regulating the pressure of the pads upon the face of the user, said means including U-shaped brackets associated with said pads, and set screws operatively associated with said pads, arms and 95 U-shaped brackets.

2. In a device of the class described, a U-shaped member, a series of arm members connected to the ends of said U-shaped member, a series of arm members connected to the intermediate portion of said U-shaped member, and springs associated with both series of said arm members to prevent the spreading apart of said arm members. 100

3. In a device of the class described, a 105 U-shaped member comprising a pair of L-shaped sections, an arm member connected to the upper end of each section, said arm members having a rivet and slot connection permitting the adjustment of said arm members, and a series of arm members connected to the foot portions of said L-shaped members. 110

4. In a device of the class described, a pair of L-shaped members having a rivet and slot 115 connection at their foot portions, arm members at the upper ends of said L-shaped members having rivet and slot connection, said rivet and slot connection of the foot portions of said L-shaped members cooperating with said rivet and slot connection of said arm members for lateral adjustment of the device, and arm members pivoted at the foot portions of said L-shaped members. 120

5. In a device of the class described, a pair 125 of L-shaped members, rivet and slot connection at the foot portions of said L-shaped members, arm members connected to the upper ends of said L-shaped members, rivet and slot connection at said arm members, the 130

- foot portions of said L-shaped members remaining in parallel relation with said arm members, and arm members connected to the foot portions of said L-shaped members.
- 5 6. In a device of the class described; a central member; arm members connected at the upper portion of said central member; arm members connected at the lower portion of said central member; lower sections connected to the last named arm members; and rivet and slot connections between said last named arm members and said lower sections facilitating the relative adjustment of said last named arm members in respect of said 10 lower sections and of said lower sections in respect to said last named arm members; said central member, both series of the arm members and said lower sections being adapted to assume a substantially rectangular
- lar formation during the operative position 20 of the device.
7. In a device of the class described; a central member; arm members connected at the upper portion of said central member; arm members connected at the lower portion 25 of said central member; lower sections connected to said last named arm members; said central member, both series of the arm members and said lower sections of one series of the arm members being adapted to 30 assume a substantially rectangular formation during the operation of the device; and springs connecting both series of said arm members preventing them from spreading apart. 35

In testimony whereof I affix my signature.

ZOFIA YACHNO.
